UNITED STATES PATENT OFFICE.

ABRAHAM ROSENBERG, OF BROOKLYN, NEW YORK.

EXERCISER.

1,275,757.

Specification of Letters Patent. Patented Aug. 13, 1918.

Application filed January 17, 1918. Serial No. 212,329.

To all whom it may concern:

Be it known that I, ABRAHAM ROSENBERG, a citizen of the United States, residing in Brooklyn, in the county of Kings and State 5 of New York, have invented certain new and useful Improvements in Exercisers, of which the following is a specification.

This invention relates to improvements in exercisers and has as its special object the 10 provision of an apparatus adapted for the use of children or adults whereby the limbs and body may be thoroughly exercised.

A further object is to provide a device which may be cheaply manufactured and 15 readily operated, even by young children, so as to provide amusement and pleasure without danger.

Another object is to provide a device which, when in use, does not interfere with, 20 or damage, articles of furniture or the surroundings, including the floor or carpets on which it rests, the device being safe when used by a strenuous child, as it will not overturn and while having the functions of a 25 rocker, is in itself rockerless, means also being provided whereby its equilibrium is normally maintained.

Its use as an exerciser is found valuable in 30 gymnasiums and hospitals in the cure of invalids suffering from back-sprain, etc., and is highly beneficial to anemics when operated in the open air.

These and other like objects are attained by the novel construction and combination 35 of parts hereinafter described and shown in the accompanying drawing, forming a material part of this disclosure, and in which:—

Figure 1 is a perspective view, showing an 40 exerciser made in accordance with the invention, and

Fig. 2 is a vertical sectional view, taken substantially through the center of the same.

In carrying out the invention, use is made of a platform 10, having arcuate ends 11, 45 the side elements being rigidly connected by cross bars 12. Secured to lower surface of the platform are contact elements 14, preferably made of rubber or like pliable material, so as to avoid damage to the carpet or floor 50 upon which the apparatus may rest.

Rising from the center of the side elements of the platform are upright standards 55 15, containing openings, here shown to be arcuate slots 17, in which are mounted spindles 18, extending from flanges 19, which are secured upon the opposite sides 20, of a

movable element which may take any preferred form, as that of a hobby-horse, sled, car or carriage, provided with a flooring 21, a seat 22, in connection with the back rest 60 23, and a foot or dash board 24, at the front, the car being an adequate size to contain one or more persons as may be desired.

Attached to the back-rest 23 and the foot board 24, respectively, by brackets 26, are 65 open hooks 27, in which are engaged the ends of helically wound tension springs 28, the opposite ends of which are engaged with similar hooks 29, secured to brackets 30, fixed upon the front and rear elements of the 70 platform at spaced distances apart, as can best be seen in Fig. 2, and it is to be noticed that the springs are so engaged with the hooks that they may be readily removed therefrom, while the car itself may be maneuvered so that the extending spindles 18, may be withdrawn from the slots 17, permitting the structure to be readily dismounted. The shape of the slots is obviously such 75 that the car will, by gravity, assume normally a central position with reference to the supporting standards.

It is to be understood that the word "car" is to be construed as embracing any suitable element upon which a person may rest and 80 actuate the structure.

In operation, a person sitting upon the seat may, by movement of the body or the limbs, cause the car to oscillate something in the manner of a rocker, this movement being 90 materially augmented by reason of the springs, while a slight to and fro movement is attained, due to the slots in the standards, thereby giving a pleasurable and exhilarating sensation to the rider, calling 95 into action the muscles of the back in a beneficial manner, tending materially to strengthen and improve the same.

While I have shown and described a working embodiment of the exerciser, I do 100 not desire to be held strictly to the exact construction set forth, as manifestly the same may be very considerably modified without departing from the spirit of the invention.

Having thus described my invention what 105 I claim as new and desire to secure by Letters Patent, is.

1. In an exerciser the combination with a platform having cushioned contacts adapted to rest upon a substantially level surface, of 110 a pair of standards arranged centrally on the sides of said platform, spindles rotatably

mounted in said standards, means permitting said spindles to move limitedly to and fro in their bearings, a car supported by said spindles, and a plurality of springs attached 5 at one end to the front and rear of said car, and to the front and rear of said platform at their other ends whereby said car is resiliently held in a normally central position.

2. In an exerciser, the combination with a 10 platform having cushioned feet secured upon its lower surface and adapted to rest upon a substantially level surface, of a pair of standards rising from the sides of said platform, arcuate slots formed at the upper end

of said standards, a car adapted to enter between said standards, spindles rigidly engaged upon the sides of said car, said spindles being engaged within the slots, means in said car for the support of the rider, hooked brackets attached respectively, to 20 the front and rear of said car, similar hooked brackets at the front and rear of said platform, and tension springs between said hooked brackets whereby said car is normally held in adjustment. 25

In testimony whereof I have signed my name to this specification.

ABRAHAM ROSENBERG.
